ABSTRACT

A transport roller for forwarding sheets bearing unfused electrostatographic images in copying apparatus comprises a core with a coiled spring wound therearound, the axis of the coils surrounding the core. When the roller is used a minimal distortion or smearing of the powder images occurs.

TRANSPORT MEANS FOR SHEETS

This invention relates to transport means for sheets. In particular the invention relates to a transport roller for forwarding sheets of paper bearing unfused electrostatographic powder images.

In common forms of electrostatographic copying apparatus, an electrostatic image is formed on a photoconductive surface, such as the surface of a drum, by charging the drum and exposing it to a light image, so that it is selectively discharged. The image is then developed by one of the well known methods such as by cascading toner particles over the surface of the drum such that they adhere to the charged areas of the drum in the image pattern. The so developed image is then transferred to a copy sheet, such as a sheet of paper, which is urged against the surface of the drum. The sheet is subsequently forwarded to a fusing zone, wherein heat fusing or solvent vapour fusing of the powdered image takes place. The sheet must be transported from the station whereat it contacts the drum to the fusing zone and this transportation can present difficulties caused by the unfused powdered image becoming smeared or otherwise disturbed. Thus, the toner material may itself be disturbed, and the electrostatic image may also be disturbed, particularly in dry developing situations, where, in contrast to wet development, no insulating liquid is present to protect the electrostatic image. Such a liquid, in wet developing, protects the electrostatic image and also protects the toner from a roller surface.

We have found that a sheet bearing an unfused electrostatographic powder image can be forwarded without the image becoming smeared by a transport means including a transport roller which comprises a core about which is wound a coil spring with the axis of the coils of the spring surrounding the core.

Thus, the present invention provides a transport roller for forwarding sheets bearing unfused electrostatographic powder images including a core about which is wound a coil spring with the axis of the coils of the spring surrounding the core.

While the invention can be applied to both wet and dry developed copy sheets, and any other type of sheet, it is particularly advantageous with dry development where difficulty has previously been particularly encountered in forwarding copy sheets.

Suitably, the axis of the coils of the spring is itself disposed in helical form about the core, and the spacing between successive turns of the spring around the core may suitably be such that they very nearly touch or do so.

The spring is preferably electrically conductive and it is preferably made of wire. The spring is suitably stretched under light tension and suitably may be fixed at each end by means of the wire of which it is formed being inserted through a hole in the core. One suitable form of roller comprises a core of three-eighths inch diameter with a wire coil spring of outside diameter one-eighth inch wound around it. The overall outside diameter of the roller is then five-eighths inch; suitably the diameter of the wire is between 0.01 and 0.05 inches, and preferably 0.03 inches. The spring may be stretched so that at the core surface the distance between the wire in adjacent coils of the spring is equal to the wire diameter.

The invention also provides an electrostatographic copying machine wherein electrostatic images are

formed and developed with toner particles and are then transferred to copy sheets, including such a roller for forwarding the copy sheets.

The roller may be provided in a forwarding arrangement to co-operate with any other sort of roller or surface provided that the imaged sides of the sheets contact the roller with the coil spring. It is however possible to provide two such rollers to co-operate for forwarding sheets, and this will particularly be useful in cases where double images are provided, one on each side of the sheet. The diameter of the rollers may be selected according to the size of machine and speed of forwarding required.

The reason why rollers of the invention are satisfactory for forwarding sheets bearing unfused images is not entirely clear at present. It may be that it is the fact that there is an incomplete outer surface in the outer envelope of the roller which is important, as the sheet and unfused image will only be contacted over a part of their areas when forwarded by the roller. This part or point contact may also be expected to be associated with an apparent lack of disturbance of the electrostatic field which holds the toner on the sheet during forwarding in contrast to a roller with a complete surface which might itself become charged, and thus create such a disturbance. A lack of disturbance of the image would, we believe follow from this feature. It may again be that it is the resilience of the rollers which is important, or, again that the various factors are together required in a satisfactory roller.

While individual coils of the spring may deform radically they will probably be tangentially movable more easily. Accordingly, it may, again, be the case that, when forwarding a sheet, the coils adjust their position slightly to avoid contact with image material on the sheet.

In order that the invention may be more clearly understood, the following description is given by way of example only with reference to the accompanying drawings in which:

FIG. 1 is a longitudinal side view of one form of roller according to the invention; and

FIG. 2 is a sectional view taken upon the line AA of FIG. 1;

The roller shown in FIGS. 1 and 2 of the drawings comprises a core 1 surrounded by a wire coil spring 2. Hub shafts 4 extend from the end of the core 1. The hub shafts extend into bearings in frame members 7 of an electrostatographic copying machine. For clarity the frame members are shown cut away and other parts of the machine, which are familiar to those skilled in the art are again not shown for clarity. The spring 2 is fixed on the core by the wire of the spring having a straight portion 3 inserted through a hole 5 in the core at each end thereof. An end of the straight portion is bent to prevent unwanted withdrawal. The spring is wound in helical fashion around the core under light tension, and on the interior of the winding at the surface of the core adjacent coils of wire are approximately a distance apart equal to their diameter. Successive windings touch or nearly touch. A roller of the type illustrated has been fitted into an electrostatographic copying machine between the image transfer point and the fusing unit, and was driven in co-operation with a rubber roller and with a slight pressure thereagainst. Over 25,000 copies were made and passed between the two rollers

without any effect on the unfused powder images contained on the sheets.

I claim:

1. An electrostatographic copying machine wherein electrostatic images are formed and developed with toner particles and are then transferred to a copy sheet, said machine including a transport roller for forwarding sheets bearing unfused powder images, said transport roller having an axis about which it is rotatable and comprising in combination an elongate core extending lengthwise of said axis and a coil spring, having convolutions wound about an axis said coil spring axis being wound in turns around said core.

2. A copying machine as claimed in claim 1 and wherein said axis of said coil spring is helically disposed around said core.

3. A copying machine as claimed in claim 1 and

wherein successive turns of said coil spring longitudinally of said core touch one another.

5 4. A copying machine as claimed in claim 1 and wherein the spacing of successive turns of said coil spring along said core is such that successive turns are closely spaced.

5 5. A copying machine as claimed in claim 1 wherein said spring is of wire.

10 6. A copying machine as claimed in claim 1 wherein said spring is stretched under light tension about said core.

15 7. A copying machine as claimed in claim 6 wherein the coil spring comprises convolutions of a filament touching said core with the distance between adjacent convolutions of the spring where they touch the core being equal to the diameter of said filament.
